UNITED STATES PATENT OFFICE.

CHARLES P. McDougall, of Indianapolis, Indiana.

DESIGN FOR A KITCHEN-TABLE:

SPECIFICATION forming part of Design No. 30,743, dated May 9, 1899.

Application filed September 27, 1897. Serial No. 653,262. Term of patent 7 years.

To all whom it may concern:

Be it known that I, CHARLES P. McDougall, a citizen of the United States, residing at Indianapolis, in the county of Marion and State of Indiana, have invented and produced a new and original Design for Kitchen-Tables; and I do declare the following to be a full, clear, and exact description of the same, reference being had to the accompanying drawings, forming a part thereof.

Figure I is a perspective of a kitchen-table, showing my new design. Fig. II is a perspective of the same tilted to show the design of the under portion of the table.

5 My new design relates to the unitary design of the table as a whole.

10 The design comprises a rectangular top portion 1, supported near each corner by legs 2, connected by the end boards 3 near their upper ends and the cross-bar 4 near their lower ends, as shown. The drawer-fronts 5 are shown along one side of the table in the upper portion. The bar 6 extends from one cross-bar 4 to the other, meeting them almost centrally. Between said longitudinal bar 6 and the upper portion of the table appears the design of two bins 7, separated somewhat and of peculiar conformation. The top, the bottom, and the sides of said bins are parallel 15 with the longitudinal bar 6 and the top of the table. At the bottom of each end there is an A-shaped figure 8. The peculiarity of the design or conformation of said bins lies chiefly in their form in cross-section—in other words,

in the form of the ends, as shown. The outline of said ends, beginning at what may be called the "front," of the table design, is in the form of a very gradual curve downward and rearward, as shown. The degree of curvature, however, of such outline increases from front to rear until it reaches the point 9 at the rear, where the degree of curvature is very considerable, as shown. There the outline forms a sharp return-bend between the points 9 and 10, and from the point 10 the degree of curvature rapidly diminishes along the upper outline of said ends to a point about midway between the front and rear portions of said bins, and from that point to the front portion the degree of curvature is almost imperceptible, the line being substantially straight, as shown. The legs are turned down, so as to divide them into four sections. The upper portion is square in cross-section, the second portion round, the third, to which the cross-bars 4 are secured, is square, and the lowest round and tapering somewhat.

What I claim as my invention, and desire to secure by Letters Patent, is—

The design for a kitchen table or cabinet, substantially as shown and described.

In testimony whereof I affix my signature in presence of two witnesses.

CHARLES P. McDougall.
